UNITED STATES PATENT OFFICE

158,500

SHOE

Benjamin Plotnick, Philadelphia, Pa.

Application December 29, 1949, Serial No. 6,915

Term of patent 14 years

(Cl. D7—7)

To all whom it may concern:

Be it known that I, Benjamin Plotnick, a citizen of the United States, residing at 5809 Woodcrest Avenue, in the city and county of Philadelphia, Commonwealth of Pennsylvania, have invented a new, original, and ornamental Design for a Shoe, of which the following is a specification, reference being had to the accompanying drawings, forming part thereof.

Fig. 1 is a perspective view of the shoe showing my new design. The view is taken looking from one side.

Fig. 2 is a perspective view of the shoe taken from the side opposite from that on which Fig. 1 was taken.

I claim:

The ornamental design for a shoe, substantially as shown.

BENJAMIN PLOTNICK.
